CORNER CABINET WITH REVOLVING SHELVES

Harry R. Trout and Frederick M. Hill, Pittsburgh, Pa.,
assignors to American Radiator & Standard Sanitary
Corporation, Pittsburgh, Pa., a corporation of Dela-
ware

Application January 2, 1953, Serial No. 22,974

Term of patent 14 years

(Cl. D33—19)

Figure 1 is a view in front elevation of a corner cabinet with revolving shelves illustrating the door in an open position.

Fig. 2 is a view in front elevation of the cabinet shown in Fig. 1 with the door closed.

Fig. 3 is a vertical cross sectional view of the cabinet taken along the line 3—3 of Fig. 2, and

Fig. 4 is a horizontal cross sectional view thereof taken between the inside shelves along the line 4—4 of Fig. 2.

We claim:

The ornamental design for a corner cabinet with revolving shelves, substantially as shown.
